GLAZING-MACHINE.

1,342,450.

Specification of Letters Patent.

Patented June 8, 1920.

Application filed January 30, 1919. Serial No. 273,988.

To all whom it may concern:

Be it known that we, STEPHEN A. KOST and WILLIAM YAEGAR, citizens of the United States, and residents of Buffalo, in the county of Erie and State of New York, have invented new and useful Improvements in Glazing-Machines, of which the following is a specification.

This invention relates to a glazing machine which is designed to apply a liquid glazing cement or paste to the joints between panes of glass and the sashes or frames of green houses on which the same are mounted for the purpose of producing a tight joint between the same.

Machines for this purpose, as heretofore constructed, required the use of both hands for their operation which made it difficult to apply the glazing material to the frames or sashes and also reduced the amount of work which a man can do particularly when operating upon the roof of a green house which necessitated holding on to stationary parts in order to enable the operator to keep his place while applying the glazing material.

It is the object of this invention to provide a glazing machine which is automatic in its operation of discharging the material from the supply magazine and which can be controlled by the use of a single hand for applying the glazing material, leaving the other hand free to hold on to the support for insuring the safety of the operator.

In the accompanying drawings: Figure 1 is a longitudinal section of our improved glazing machine. Fig. 2 is a side elevation of the same. Figs. 3 and 4 are cross sections taken on the correspondingly numbered lines in Fig. 1. Fig. 5 is a cross section taken on line 5-5, Fig. 2.

Similar characters of reference refer to like parts throughout the several views.

6 represents the magazine, tank or barrel of the glazing machine which is adapted to receive in its front end the charge of glazing material which is to be applied to the frames or sashes and the panes of a greenhouse or similar structure, this magazine being preferably constructed of metal in the form of a cylinder, as shown in Figs. 1, 2 and 4.

At its front end this barrel is provided with a cap or head 7 which is preferably

constructed in the form of a tapering funnel and detachably connected at its large end with the front end of the barrel by means of a screw joint 8 as shown in Fig. 1, or by any other suitable means, so that upon removing this front cap a charge of glazing material may be introduced into the barrel preparatory to depositing the same where required. The discharge of this material from the barrel is controlled by means of a valve which may be variously constructed but in the form shown in the drawings, as an example, the same comprises a body 9 having a passage 10 therethrough the inlet end of which is connected by means of a screw joint with the outlet of the funnel-shaped cap 7 while the discharge end of this passage is connected with a nozzle 11 by which the glazing material is deposited. A rotary stopper or plug 13 of tapering form engages with a correspondingly shaped valve seat 12 which intersects the passage of the valve body. This stopper or plug is provided with a diametrical port or passage 14 which upon turning the plug so that this port is arranged crosswise of the valve body, as shown in Figs. 1 and 5, will close the valve and prevent the discharge of glazing material but which upon being turned so that this port registers with the passage of the valve body will permit the glazing material to escape from the supply barrel or magazine. This valve plug is held tightly against its seat by means of a screw shank 16 arranged at its small end, a washer 15 applied to this screw shank and bearing against the adjacent end of the valve body and a screw nut 17 applied to this screw shank and engaging with the outer side of the washer, as shown in Fig. 5. At its opposite or large end the valve plug is provided with an oblong valve stem 18 whereby the valve plug may be turned into its opened or closed position.

When using this device in applying the glazing material to the sash and panes the operator grasps the barrel by one hand and in order to leave the other hand free to hold on to the sash or other available support of the building, an operating mechanism is provided for the valve which can be controlled by a finger of the same hand which holds the supply barrel. The valve operating mechanism having this capacity may

be variously constructed but that which is shown in the drawings is suitable and owing to its simplicity of construction it is preferred. As shown in Figs. 2 and 5 this preferred form of valve operating mechanism comprises a segmental gear 19 which is secured to the valve stem by providing the hub of this gear with an oblong opening which receives the stem 18 of the valve, and 10 a cotter pin 20 or similar device passing through an opening in the stem adjacent to the outer side of the gear. Meshing with this gear segment is a longitudinally reciprocating gear rack 22 guided on a bracket 21 which is preferably formed on the front cap 7 and provided with an outer longitudinal guide flange 23 engaging with the outer longitudinal edge of the gear rack. The gear rack is provided with a longitudinal 15 slot 24 which receives a retaining screw 25 secured to the adjacent part of the supporting bracket, as shown in Figs. 2 and 5. 20 26 represents a longitudinal operating rod which is arranged lengthwise on one side of 25 the lower barrel cap and connected at its front end with the rear end of the rack while its rear part is guided in a lug 29 projecting laterally from the front barrel cap and its rear end terminates in a finger piece 26 or handle 27. Surrounding this operating 30 rod is a helical spring 28 which bears at its front end against the rear end of the gear rack while its rear end bears against the guide lug 29. This spring when free 35 constantly tends to move the gear rack forwardly and turn the gear segment and the valve plug in the direction for closing the valve by shifting the port of the valve plug out of register with the passage 40 through the valve body. The forward and backward movement of the gear rack is limited so as to stop the rotation of the valve plug in either direction when the latter is opened or closed by engagement of the front 45 and rear ends of the guide slot 24 with the screw 25 which latter operates as a stop for this purpose.

By taking hold of the supply barrel with 50 one hand and pulling with one finger of the same hand backwardly on the handle 27 the operator is able to open the valve and discharge the glazing material from the cylinder and also direct the discharge nozzle along the surface intended to receive the 55 glazing material. The other hand of the operator is therefore left free to hold on to any available support for insuring his safety while performing the glazing operation, thereby enabling the operator to work much 60 more rapidly and without liability of falling. The instant the operator releases the rearward finger pressure on the operating rod the spring 26 automatically moves the gear rack forwardly so as to close the discharge valve and prevent the escape of fur- 65

ther material. By this means the delivery of material from the supply barrel may be accurately controlled so that no more material than necessary is deposited, thereby avoiding waste and effecting greater economy in the cost of glazing as compared with the methods heretofore employed. 70

The glazing material is discharged from the supply barrel by a plunger or piston which slides lengthwise therein and which 75 may be variously constructed but which in the form shown in the drawings comprises a disk shaped body 30 of cork or similar material and two metal retaining disks 31, 32 applied to the front and rear sides of the 80 cork body and connected with each other by means of a tubular hub of sleeve 33 passing through corresponding openings in the central parts of the cork and retaining disks and connected at its lower end by means of 85 a screw joint with the front disk and provided at its rear end with an annular flange 34 bearing against the rear side of the rear disk, as shown in Fig. 1.

Preparatory to filling the front part of 90 the supply barrel with glazing material the plunger or piston is moved into its rear-most position within the barrel, and upon moving this plunger forwardly the material is discharged from the barrel when the 95 valve is open. The means whereby the plunger is operated are so constructed that they operate to shift the plunger forwardly automatically when the valve is opened. These means in their preferred form comprise a comparatively stiff helical evacuating spring 35 which is arranged within the rear part of the supply barrel and engages its front end with the rear retaining disk to which the foremost convolution of the 100 spring is preferably secured by means of a clip 36 as shown in Fig. 1. The rear end of this spring engages with a follower 37 which is movable lengthwise in the rear part of the barrel, the rearmost convolution of this spring being preferably secured to the follower by means of a clip 38. At 105 its rear end the supply barrel is provided with a head 39 which may be secured thereto by means of a screw joint, as shown in 115 Fig. 1, or by any other suitable means. In the central part of this rear head the same is provided with an internally screw-threaded opening 40 which receives a compressor screw 44 which is preferably of 120 tubular form. A connection is effected between the front or inner end of this compressor screw and the follower which is preferably so constructed that these parts are compelled to move lengthwise together 125 but the compressor screw is free to turn independently of the follower. This connection in its preferred form, as shown in Fig. 1, comprises an annular flange 41 arranged on the inner end of the compressor 130

screw and bearing against the rear side of the follower and a retaining ring 42 secured to the rear side of the follower by screws 43, or otherwise, and overhanging the rear side of the flange and the compressor screw. Rotation of the compressor screw is effected by means of a handle 45 which preferably has the form of a wheel secured to the rear end of the compressor screw externally of the supply barrel and forming practically a part of this screw. Upon turning the compressor screw in one direction or the other the follower is caused to move forwardly or backwardly within the pump barrel.

Extending lengthwise through the compressor screw, the follower, the evacuating spring and the tubular hub of the piston is a retracting screw 46 which is provided at its front end with a head 51 bearing against the front side of the front plunger disk while its rear end, which extends beyond the rear end of the compressor screw, is provided with a handle 47 for turning the same. In rear of the compressor screw is arranged a screw nut which is adapted to be engaged with or disengaged from the external screw thread of the retracting screw which screw nut is so mounted that the same is movable back and forth with the compressor screw 44 and the handle 45. This screw nut in its preferred form is split into two sections 48, 48 which are adapted to engage with opposite sides of the thread of the retracting screw and are pivotally connected on one side with each other and with the handle of the compressor screw by means of a pintle 49. The opposite ends of the screw nut sections are adapted to be interlocked with each other while their internal thread sections are engaged with the thread of the retracted screw. This connection may be effected in a variety of ways that shown in the drawings being merely an example of one suitable for this purpose and consisting of a locking pin 50 passing through corresponding openings in the free ends of the screw nut sections, as shown in Figs. 1, 2 and 3.

Preparatory to filling the front part of the supply barrel with a charge of glazing material the compressor screw is turned backwardly until the follower is close to the rear head of the barrel and the retracting screw is turned backwardly while the screw nut sections are in engagement therewith so that this retracting screw moves rearwardly relatively to the compressor screw together with the plunger and causes the evacuating spring to be compressed between the follower and the plunger. While the plunger is in this position and the evacuating spring is flexed the operator removes the front cap from the barrel and introduces a charge of glazing material into

the latter after which the front cap together with the valve mechanism mounted thereon is reapplied to the barrel. The locking pin 50 may now be moved from the screw nut sections and the latter are swung apart so that they are disengaged from the threads of the retracting screw. This releases the retracting screw and the plunger and permits the latter to be pushed forwardly by the evacuating spring which latter is now free to operate if the valve is open, but if at this time the valve is closed the pressure of the plunger against the glazing material will not be able to discharge the same from the barrel. While in this condition the operator may take the barrel in one hand and pass the delivery nozzle over the surfaces intended to receive the glazing material and at the same time he may employ one finger of the hand which grasps the barrel for operating the handle of the valve operating mechanism for operating the valve so that the material will be discharged from the nozzle automatically by the resilience of the evacuating spring.

When the plunger has been moved forwardly to such an extent that the tension of the evacuating spring has been exhausted and the plunger has not yet reached the front end of the barrel so that still a quantity of the glazing material is contained therein this spring can be again placed under tension for continuing its automatic operation when the valve is opened by turning the compressor screw forwardly through the medium of the handle 45 whereby the follower is again advanced relatively to the plunger and the evacuating spring is again compressed between the latter and the follower, this position being indicated in Fig. 1. The automatic discharge of the glazing material from the barrel will now be resumed through the expansion of the evacuating spring the instant that the valve is opened in the same manner in which this was effected when the plunger and the follower were in their rearmost position.

It will thus be apparent that the spring can by this means be repeatedly placed under compression step by step from its rearmost position in the barrel toward the front end of the same until the plunger has reached its foremost position in the barrel and practically the entire charge of glazing material has been discharged automatically from the barrel.

Owing to the simplicity of construction of this glazing machine and the ease with which the same may be operated by the use of one hand of a person doing the work, a much greater amount of glazing can be accomplished within a given time than has been possible by the use of devices heretofore used and at the same time insuring the

safety of the operator and effecting a considerable economy in the use of glazing material.

We claim as our invention:

- 5 1. A glazing machine comprising a barrel adapted to contain a charge of glazing material and having an outlet at its front end, a plunger movable lengthwise in said barrel, a spring bearing against said plunger and adapted to move the latter forwardly, means for putting said spring under tension and means for positively returning said plunger.
- 10 2. A glazing machine comprising a barrel adapted to contain a charge of glazing material and having an outlet at its front end, and a head at its rear end which is provided with a screw thread opening, a plunger movable lengthwise in said barrel, a spring bearing at its front end against said plunger, a follower bearing against the rear end of said spring, and a compressor screw 20 engaging with said follower and working in said threaded opening.
- 25 3. A glazing machine comprising a barrel adapted to contain a charge of glazing material and having an outlet at its front end, and a head at its rear end which is provided with a screw thread opening, a plunger movable lengthwise in said barrel, a spring bearing at its front end against said plunger, a follower bearing against the rear end of said spring, a compressor screw 30 working in said opening and engaging with said follower, and means for retracting said plunger.
- 35 4. A glazing machine comprising a barrel adapted to contain a charge of glazing material and having an outlet at its front end, and a head at its rear end which is provided with a screw thread opening, a plunger movable lengthwise in said barrel, a spring bearing at its front end against

said plunger, a follower bearing against the rear end of said spring, a hollow compressor screw which works in said opening and is connected with said follower, a retracting screw arranged within the hollow screw and connected with said plunger, and a screw nut mounted on the hollow screw and receiving said retracting screw.

5. A glazing machine comprising a barrel adapted to contain a charge of glazing material and having an outlet at its front end, and a head at its rear end which is provided with a screw thread opening, a plunger movable lengthwise in said barrel, a spring bearing at the front end against said plunger, a follower bearing against the rear end of said spring, a hollow compressor screw 50 which works in said opening and having a rotatable connection with said follower, a retracting screw arranged in the hollow screw and having a rotatable connection with said plunger, and a screw nut mounted 60 on said hollow shaft and receiving said retracting screw.

6. A glazing machine comprising a barrel adapted to contain a charge of glazing material and having an outlet at its front end, and a head at its rear end which is provided with a screw thread opening, a plunger movable lengthwise in said barrel, a spring bearing at its front end against said plunger, a follower bearing against the rear 75 end of said spring, a hollow compressor screw which works in said opening and is connected with said follower, a retracting screw arranged within the hollow screw and connected with said plunger, and a screw nut mounted on said hollow screw and divided into sections which are adapted to be engaged with and disengaged from the threads of said retracting screw.
